UNITED STATES PATENT OFFICE.

GEORGE J. WILLETT, OF MILWAUKEE, WISCONSIN.

SAFETY-LOCK FOR HAMMER-HANDLES.

1,115,627.

Specification of Letters Patent.

Patented Nov. 3, 1914.

Application filed August 18, 1913. Serial No. 785,322.

To all whom it may concern:

Be it known that I, GEORGE J. WILLETT, a citizen of the United States, and residing in Milwaukee, in the county of Milwaukee and State of Wisconsin, have invented certain new and useful Improvements in Safety-
Locks for Hammer Handles, of which the following is a specification.

My invention relates to safety devices for use in connection with sledges and has particular reference to a novel lock by means of which the handle is securely held in place in the head.

It is not uncommon in the use of heavy hammers or sledges for the head to become separated from the handle, many times causing serious injury to fellow workmen. This is a hazard which has been sought to be overcome in many ways without marked success.

An object in the construction of such a device should be to provide holding means for the handle which shall be independent of the head itself and which shall not rely on the fastenings entering the material composing the handle. Any fastenings which rely for their holding power on their entering engagement with the wood of the hammer handle are insecure and tend to weaken the handle.

My device contemplates the use of a pair of wedging clamps which shall act to grasp the hammer handle at a point close to the head and clamp the same in such manner that separation from the head is impossible. Such a fastening device is so located as to be out of the way, cannot become out of order and is very easily applied.

The invention will be more readily understood by referring to the accompanying drawings, wherein, Figure 1 is a side elevation of a hammer constructed in accordance with my invention; Fig. 2 is a section on the line 2--2 of Fig. 1; Fig. 3 is a section on the line 3--3 of Fig. 2, and, Fig. 4 is a face view of the ferrule which is riveted to the hammer head.

Referring more particularly to the drawings it will be seen that the illustration is of a common sledge having a head 10, and centrally apertured at 11, to provide for the handle. Small apertures 12, are provided at either side of the central apertures, these openings accommodating rivets 13, by means of which a ferrule or clamp 14, is secured to the inside face of the head. This clamping member is provided with a central opening

15, which opening near one face of the clamp is enlarged as at 16, thus providing a shoulder 17, against which the flanges 18, of the handle clamps 19, 20, may engage. These clamps are semi-circular in cross section and wedge-shaped in longitudinal section being adapted to fit snugly the portion of the handle 21, next to the hammer head. As is usual, the aperture through the hammer head is of slightly reduced cross section near the middle portion, the handle being tapered at the point where it passes through the head. After being seated in the head the handle is enlarged to completely fill the space, as best shown in Fig. 3. This provides a slightly enlarged portion on the hammer at the point where it enters the head, which point is reduced in size at a short distance rearward of the handle. The wedge-shaped clamping members engage this slight enlargement and due to the clamping action hold the handle securely against accidental removal.

The application of the clamping device may be as follows: Prior to inserting the handle in the head, the clamping member 14, is placed on the handle, then the wedge-shaped members 19, are placed in position at a point on the reduced portion of the handle. The head is then located on the handle, whereupon the clamping member is forced up into engagement with the head and the rivets 13 applied. This serves to rigidly unite the clamping member 14 to the head and to wedge the semi-circular members on the handle. Accidental removal of the handle is thereafter impossible as even though the handle should become loosened in the head it would be securely held by the clamps.

It is obvious that modifications may be made in the construction shown and such modifications as are within the scope of my claims I consider within the spirit of my invention.

I claim:

1. In a device of the class described, the combination of a head and a handle, a ring surrounding said handle and secured to said head, and a pair of wedge-shaped clamps engaging said ring and co-operating with the surface of said handle whereby to prevent the accidental removal of said handle, substantially as described.

2. In a hammer, the combination of a head, a ring rigidly secured to said head, said ring having an undercut aperture there-

through, said aperture registering with an aperture in the head, a handle seated in said head, said handle having a wedge-shaped portion, and segmental wedge-shaped clamping members coöoperating with the wedge-shaped portion on said handle, said segmental members having a shoulder adapted to

be seated in the undercut recess in said clamping ring, substantially as described.

GEORGE J. WILLETT.
